UNITED STATES PATENT OFFICE.

FRANK DUTCHER, OF VERSAILLES, PENNSYLVANIA, ASSIGNOR TO CENTRAL RAILWAY SIGNAL COMPANY, OF PITTSBURGH, PENNSYLVANIA, A CORPORATION OF NEW JERSEY.

RAILWAY SIGNAL-TORPEDO.

1,158,994.

Specification of Letters Patent.

Patented Nov. 2, 1915.

Application filed January 11, 1915. Serial No. 1,630.

To all whom it may concern:

Be it known that I, FRANK DUTCHER, a citizen of the United States, residing at Versailles, in the county of Allegheny and 5 State of Pennsylvania, have invented certain new and useful Improvements in Railway Signal-Torpedoes, of which the following is a specification, reference being had therein to the accompanying drawing.

10 This invention relates to improvements in railway signal torpedoes and pertains particularly to improved means for attaching a spring rail clasp to a paper or fiber torpedo case.

15 The object of my invention is to provide a means for attaching a spring rail clasp to a fiber or paper torpedo case in such a manner that the pulling open or separation of the ends of the clasp to attach it to the 20 rail will not tend to separate the folded portions of the case.

A further object of the invention is to provide the spring clasp attaching means with clamping ears for firmly clamping the 25 outer fold of the case in its folded position so that it can not become displaced either in shipment or in handling.

Referring now to the accompanying drawings: Figure 1 is a perspective view 30 of a paper or fiber case torpedo with my improved spring clasp attachment applied thereto and the torpedo shown in position on the railroad-rail. Fig. 2 is a sectional view on the line 2—2 of Fig. 1. Fig. 3 is 35 a sectional view on the line 3—3 of Fig. 2. Fig. 4 is a perspective view showing the torpedo case opened up before the folds are in their permanent, folded position.

The type of torpedo case to which my 40 improvement is applied is known as the "wedge shape" form, and it is made from a blank of sheet paper. The central body portion is forced outward into a wedge-shaped portion 1, which forms on the inner side 45 thereof a recess 2. Within this recess 2 the explosive 3 is placed, and this explosive is of the tablet form. This central portion 1 of the torpedo case is provided with end flanges 4, and the sides of the central portion 1 is provided with the two side flaps 5 which are turned inward as shown in Fig. 4 over the explosive 3. The flange 4, at one 50 end of the central portion, is provided with an end flap 6 which is of a length and width substantially corresponding to the length

and width of the central portion 1 and its flanges 4. The flange 4 at the other end of the central portion, is provided with an end flap 7, and this end flap 7 is also of a length and width substantially corresponding to the 55 length and width of the central portion 1 and its flanges 4.

My present improvement comprises a plate 8 which is applied to the inner side of the end fold or flap 7, and connected thereto by the ears 9 which are bent around on the outer side of the flap 7 and compressed tightly thereon, thus uniting the plate 8 to the fold 7. The plate 8 and fold 7 are provided with registering openings 10 made 60 of a size to receive the spring clasp 11, and the plate between these openings is bulged outward as shown at 12 Fig. 3 to permit the spring clasp to be threaded through these 65 openings as shown in Fig. 4.

After the plate 8 is applied to the flap 7 and the spring clasp threaded through the 70 openings 10, the plate and flange are folded inward over the side flaps 5, and they are 75 suitably cemented together by a water-proof 80 cement. Then the flap 6 is folded on the outer side of the flap 7 with cement between them, and ears 13 at the corners of the flap 7 are bent over against the outer side of the flap 6 and tightly clamped thereto which 85 form clamps holding the folded portions of the case in their proper positions and against displacements. These ears 13 come 90 under the corners of the flanges 4 which are located at points beyond the explosive 3 so 95 that there is no danger of exploding the charge when the ears 13 are forced downward tightly against the outer side of the flap 6. If desired, the flap 7 may be provided 100 with one or more perforations 14, and these 105 perforations will serve the double function of pockets for the cement and lightening the plate. If desired, the spring clasp 11 may be provided with an intermediate 110 opening 15, and the bulged portion 12 with the projection 16 adapted to enter this opening for the purpose of centrally positioning the spring clasp 11. With an attachment of this construction, the ends of the spring clasp 11 can be separated to be placed around the tread of a railroad-rail without separating the folds of the case, and this is important because any separation or break-away of the folds of flaps of the case opens up passages for water and moisture, thus

materially destroying the effectiveness of water-proof protection which is absolutely essential in railway signal torpedoes to meet the specifications and requirements of the railroad companies.

Having thus described my invention what I claim and desire to secure by Letters Patent is:

1. An improved railway signal torpedo comprising a case made up of over-lapping flaps, a plate applied to the inner side of one of said flaps, the plate and flap having openings for the passage of a spring clasp, the plate also having marginal ears adapted to be bent down in contact with the flap for holding it in position thereon.

2. An improved railway signal torpedo comprising a case, having a central portion adapted to receive an explosive charge, two end flaps adapted to be folded inward over the explosive charge, a spring clasp attaching plate applied to the inner side of the inner folded flap, the flap and plate having openings through which a spring clasp may be threaded, the plate having ears which are bent down against the outer side of the outer flap for the purpose described.

3. An improved railway signal torpedo comprising a paper case having a central portion adapted to receive an explosive compound, the central portion having two end

flaps adapted to be folded inward one over the other and under the central portion, a spring clasp attaching plate applied to the inner side of the inner end flap, said inner flap and plate having registering openings to receive a spring clasp, said plate also having ears bent on the outer side of last said flap, the plate having marginal ears which are bent downward on the outer side of the outer end flap thereby holding all of the folded flaps in their folded positions.

4. An improved railway signal torpedo, comprising a case made up of overlapping flaps, a plate applied to the inner side of one of said flaps, the plate and flaps having openings for the passage of a spring clasp, the plate having means for securing it in position thereon.

5. An improved railway signal torpedo, comprising a case made up of overlapping flaps, a plate applied to the inner side of one of said flaps, the plate and flaps having openings for the passage of the spring clasp, the plate having ears adapted to engage the flap for holding it in position thereon.

In testimony whereof I hereunto affix my signature in the presence of two witnesses.

FRANK DUTCHER.
